UNITED STATES PATENT OFFICE.

ABRAHAM SELIGSTEIN, OF MUNICH, GERMANY.

SAFETY RAZOR.

Application filed May 26, 1923. Serial No. 641,649.

To all whom it may concern:

Be it known that I, ABRAHAM SELIGSTEIN, a citizen of the German Reich, residing at Munich, Germany, have invented certain new and useful Improvements in Safety Razors, of which the following is a specification.

This invention relates to a head plate for safety razors also adapted for stropping said head plate covering the blade in the well known manner when the apparatus has to be used for shaving but being turned upside down it serves as support for the blade when the apparatus is to be used for stropping.

The combined razor and stropping devices of known type present the inconvenience, that if used as safety razor the blade is not protected by the cover-plate so that it is elastic when being used. The elasticity of the blade causes pain in the skin and cuts.

An embodiment of the invention is shown by way of example on the accompanying drawing, wherein:

Fig. 1 shows the safety razor ready to be used for the stropping of the blade.

Fig. 2 shows the improved safety razor ready to be used for shaving.

Fig. 3 shows the removable rib in side elevation partly in section and in plan view.

Fig. 4 is a similar view as Fig. 2 the head plate being shown in cross section.

Fig. 5 shows the head plate in plan view and in cross section.

According to this invention the commonly used head plate *a* of the safety razor is

subdivided into two parts, the head plate proper and into a small rib *d* which carries the guide pins *c'* and the screw bolt *c''* (Fig. 3). The head plate proper *a* has a longitudinal groove *b* (Fig. 5) for the accommodation of the rib *d* so that the apparatus may be used as safety razor in the usual manner (Fig. 2), or for stropping, in which latter case the narrow rib *d* is removed from the longitudinal groove *b* of the head plate *a*, the head plate *a* is turned upside down, as shown in Fig. 1 and the narrow rib *d* is used to hold the blade *e* on the top plate.

I claim:

In a safety razor comprising a guard plate having a convex blade supporting surface, a clamping plate having a concave blade engaging surface, a clamping bar or rib, a handle, interengaging means between the handle and bar, means to properly position a blade on either of said plates, said clamping plate being reversible whereby the blade may be clamped in convexed position between said clamping plate and bar for holding the blade for stropping or honing purposes, said clamping plate being apertured to receive the interengaging means and positioning means but being otherwise plain and unobstructed.

In testimony whereof I affix my signature in presence of two witnesses.

ABRAHAM SELIGSTEIN.

Witnesses:

ALEXEI PHILIPPOFF,
ALE HOUGHTON.
